UNITED STATES PATENT OFFICE

OSCAR HERBERT WALLIN, OF STOCKHOLM-LIDINGO, SWEDEN

HEATING APPARATUS FOR FLUID CIRCULATION SYSTEMS

Application filed April 7, 1930, Serial No. 442,396, and in Sweden November 9, 1928.

This application is a continuation in part of my previous patent application Ser. No. 323,735, filed the 4th of December, 1928 and entitled Catalytic heating device, and my present invention refers to a heating apparatus for fluid circulation systems, and more specifically to a catalytic heating device adapted to be combined with the circulation pump for the cooling medium in internal combustion engines. The main purpose of the invention is to facilitate the starting of the engine in cold weather by preheating of the cooling medium therein, and after the start the catalytic heating device forming an integral part of the apparatus may be set out of action, whereafter the pump may be run as usual for the purpose of circulating the medium used.

In most cases the cooling medium used in internal combustion engines consists of pure water, or water admixed with special ingredients for one purpose or the other, and the apparatus according to the invention is mainly intended for use in connection with such liquid cooling media, but the result will be substantially the same, even if the cooling medium to be acted upon by the heat should be of a gaseous nature.

The invention is illustrated in the accompanying drawing which shows two somewhat different modifications thereof. In the drawing:

Fig. 1 shows one modification of the invention seen in elevation partly in section, and

Fig. 2 is a partly sectional plan view of Fig. 1.

Fig. 3 shows the second modification in the same manner as Fig. 1, and

Fig. 4 is a partly sectional plan view of Fig. 3.

In the drawing such parts not needed for an explanation of the invention are omitted, and it is to be understood that the catalytic heating device, which can be constructed in many varying ways, is not claimed per se, or otherwise than in combination with the pump, as described.

The invention is chiefly intended to be used in motor cars, air-planes and the like, and in connection with the engines for such vehicles the cooling fluid system is provided

with a centrifugal pump or turbine pump coupled in series between the cooling jackets and the radiator, or radiators. Therefore the embodiments of invention shown in the drawing are supposed to include in the combined apparatus a fluid propelling means of this kind, but the invention for its utility is not limited to such kinds of propelling means only, and it may also be used in combination with pumps of other types, as will be understood from the following.

In the embodiment of invention shown in Figs. 1 and 2, the pump has the reference 1, and is provided with a suction pipe 2 and a pressure pipe 3. For many reasons it is desirable that the catalytic heating device is mounted on the suction side of the pump, especially when combined with centrifugal pumps, but said device may also be mounted on the pressure side of the pump, if desired in special instances. The main advantage in mounting the heating device on the suction side of the pump is that the pump will also be warmed up and be prevented from damages due to freezing.

The catalytic heating device consists of two main parts, i. e. the evaporator 4 and a heater 5. The construction of the evaporator 4 is of minor importance in this connection, and this part of the apparatus may be constructed in the manner described in the U. S. Patent No. 1,792,337. The evaporator serves the purpose of vaporizing the liquid fuel used, and from said evaporator the fuel gas is fed into the heater 5, in which it is subjected to flame-less combustion by means of a catalyst, such as platinic sponge or the like.

According to Figs. 1 and 2, the suction side of the pump is provided with a bulb-shaped member 6, the chamber 7 within which the catalytic combustion is to be performed being centrally positioned within said bulb-shaped member. A perforated tube 8 extends centrally into the bulb-shaped inner chamber 7 and is connected with the gas tube from the evaporator 4. A wire netting 9 (Fig. 1) is swept around the perforated tube 8 impregnated with or supporting a catalytically active material. In the space between the central tube 8 and the inner face of the bulb 6

is provided a filling material 10 of a porous or fibrous fire-resistant and heat-accumulating material, such as infusorial earth, asbestos or the like, the said filling being longitudinally penetrated by a number of perforated tubes 11 open at their upper ends for the purpose of introduction of the air needed for the combustion. Electric heating coils (not shown) may also be embedded in the filling material for the purpose of preheating the same when the combustion is to be started.

Exteriorly the bulb-shaped combustion chamber 7 is provided with ribs 12 for facilitating the transfer of heat to the fluid entering the outer bulb-shaped member 6 by the inlet 13 when passing the heater on its way to the pump.

A heating of the evaporator 4, which perhaps sometimes will be found advisable, may be effected by a hot air pipe or the like heated due to the combustion in the heater 5.

In the embodiment of invention shown in Figs. 3 and 4 the same references are used for similar parts of construction as in Figs. 1 and 2. The main difference between the embodiments is that according to Figs. 1 and 2 the fluid to be heated is passed exteriorly around the heater, but according to Figs. 3 and 4 the said fluid is passed through a central channel within the same.

Referring to Figs. 3 and 4, the heating chamber 7 is arranged in the form of an intermediate cavity between the end shields 14 and 15 of the pump, the said chamber being centrally penetrated by a pipe 16 adapted for surrounding the pump shaft 17. At a little distance around the pipe 16 there is mounted another pipe 18, and the inner-space between said pipes connects the pump inlet 2 with the pump wheel. A cylindrical perforated wall 8^a is positioned within the chamber 7 at a little distance from the interior surface of its cylindrical wall, and the catalyst 9^a is at hand on the inner side of the said perforated wall. Within the inter-space between the catalyst and the tube 18 is arranged a filling 10^a of the nature described above, such filling being longitudinally penetrated by a number of perforated inlet pipes 11^a for the combustion air, and at least some of said perforated pipes being open at their one end, the opposite end of said pipes being inter-connected by means of an annular chamber 19. If desired, this chamber may be connected with a hot air pipe extending below or otherwise combined with the evaporator 4 for the purpose of heating the same.

The combustible gas from the evaporator 4 is admitted to the inter-space at the inner side of the cylindrical wall of the heating chamber 7, and through the perforated wall 8^a it comes in contact with the catalyst thereby causing the flame-less combustion. The tube 18 is provided with ribs 20 as well ex-

teriorly as interiorly (compare Fig. 3) for facilitating the transfer of heat to the cooling medium passing the annular passage between the tubes 16 and 18.

It is obvious that the mounting together of the catalytic heating device and the pump may also be performed in other ways than those described above and shown in the drawing, and the heating device, or its heating chamber, within which the catalytic combustion takes place, may be mounted, for instance, in one of the end shields of the pump housing. This combination of the heating device and the pump is especially advantageous due to the fact that the weight and also the cost of manufacture of the combination as a whole may be reduced below the total weight and cost of manufacture respectively, if the pump and the heating device had been produced separately, and besides the mounting of the whole assembly will be simplified and the space required reduced, all of such facts being of importance in practice.

What I claim and desire to secure by Letters Patent is:—

1. An aggregate adapted to be connected as a unit in a cooling liquid circulating system for an internal combustion engine to cause the liquid to circulate through the said system and to heat the liquid contained in the said system, comprising in combination a pump having an inlet and an outlet adapted to be connected in a pipe line for the said cooling liquid and a catalytic heating device comprising an evaporator, means for transmitting liquid fuel such as gasoline to the said evaporator, a combustion chamber containing a catalyst, means for transmitting the evaporated fuel from the evaporator to the combustion chamber, and means for admittance of air into and escape of combustion gases from the said combustion chamber, the combustion chamber being housed within the housing of the pump and having a wall bounding a passage for the cooling liquid within the pump.

2. An aggregate adapted to be connected as a unit in a cooling liquid circulating system for an internal combustion engine to cause the liquid to circulate through said system and to heat the liquid in said system, comprising in combination, a centrifugal pump having an inlet and an outlet adapted to be connected in a pipe line for the said cooling liquid, a combustion chamber mounted within the inlet of the said pump in spaced relation to the walls thereof so as to be passed by the cooling liquid flowing through the said inlet, means in the said combustion chamber for catalytic combustion of an evaporated fuel such as gasoline introduced therein, an evaporator associated with the said combustion chamber, means for transmitting the fuel in a liquid state to the said evaporator, and

means for the introduction of the evaporated fuel from the evaporator into the combustion chamber.

3. An aggregate adapted to be connected as a unit in a cooling liquid circulating system for an internal combustion engine to cause the liquid to circulate through said system and to heat the liquid in said system, comprising in combination, a centrifugal pump having axially spaced end shields provided with an inlet and an outlet respectively, a casing forming a combustion chamber and an axially extending passage for the cooling liquid around the shaft of the pump interposed between the said spaced end shields, means in the said combustion chamber for catalytic combustion of an evaporated fuel such as gasoline introduced therein, an evaporator associated with the said combustion chamber, means for transmitting the fuel in a liquid state to the said evaporator, and means for the introduction of the evaporated fuel from the evaporator into the combustion chamber.

In testimony whereof I have signed my name to this specification.

OSCAR HERBERT WALLIN.
